Primary Examiner—Terry A. Pfeffer*Attorney, Agent, or Firm*—Zarley, McKee, Thomte, Voorhees, & Sease[57] **CLAIM**

The ornamental design for a dishwasher silverware basket, as shown and described.

DESCRIPTION

FIG. 1 is a perspective view of the dishwasher silverware basket showing our new design;

FIG. 2 is a side elevational view thereof;

FIG. 3 is a front elevational view thereof, the opposite side being identical;

FIG. 4 is a sectional view thereof taken along lines 4—4 of FIG. 2;

FIG. 5 is a top plan view thereof;

FIG. 6 is a bottom plan view thereof; and,

FIG. 7 is a sectional view thereof taken along line 7—7 FIG. 3.

The handle shown in broken lines in FIGS. 2 and 4 is for illustrative purposes only.

FIG. 1

FIG.4

FIG.5

FIG.6

FIG.7
